CONTAINER

John D. Brophy, New York, N. Y.

Application September 5, 1935, Serial No. 39,232

2 Claims. (CL. 229—87)

This invention relates to improvements in containers and relates more particularly to a novel container for cigarettes, cigars and the like, the container having improved closure means and means for facilitating the removal of the contents.

The more popular cigarettes are usually packed in non-rigid paper containers as contrasted with the rigid paper boxes in which the more expensive cigarettes are sold. The cigarettes are necessarily packed quite tightly in order to accommodate twenty cigarettes in a container of small and convenient size. In view of this tight packing, the user normally experiences considerable difficulty in removing the first few cigarettes.

Various containers have been devised which have means to facilitate the removal of the contents. Some of these have included perforated or scored opening portions, pull cords or tapes, etc. Virtually all of these containers have proven unsatisfactory for the reason that they have been too expensive to produce and the cigarette manufacturer, who is operating on a very close margin of profit, cannot increase the cost of each container by even one cent.

It is accordingly one of the principal objects of the present invention to provide a container having improved closure and opening means to facilitate the removal of the first cigarettes which are withdrawn from the package, which container can be produced as cheaply as the present conventional container in which the popular brands of cigarettes are sold and furthermore can be produced by the present packaging and wrapping machine with only a slight and inconsequential re-arrangement of parts.

The present non-rigid paper container for cigarettes is rectangular in transverse or horizontal section and the upper end of the container is held in this rectangular shape by means of the revenue stamp. When this stamp is broken or removed, the container immediately assumes a more rounded shape and the cigarettes are more easily removed.

In the present invention, the revenue stamp is itself employed to effect the final closure. Heretofore, the position adopted by the manufacturer for the revenue stamp has been more or less arbitrary since the only regulations provided by the Treasury Department is that the stamp be securely affixed in such a manner as to seal the package. It was considered a matter of convenience to have the two end portions extend downwardly on the side walls of the container an equal distance. In carrying out my invention,

the revenue stamp occupies substantially the same position that it occupies at present, except that one end thereof is positioned slightly more than one-eighth of an inch higher and on the opposite side of the container the other end portion extends downwardly a corresponding distance further than it does at present. This latter end is provided with a glue strip which stops just short of its end and in the process of affixing the stamp, this end portion is slightly bent or scored to cause it to extend slightly outwardly from the vertical side wall of the container.

This unglued, outwardly projecting portion functions as a tear tab which may be readily grasped by the fingers. As this tab is raised upwardly it also raises the closure flap, which is integrally formed along the upper edge of the rear wall of the container. In order to further facilitate the removal of the first few cigarettes from the package, the upper edge of the front wall of the package is formed with a small rectangular recess, the width of which is somewhat less than the width of the revenue stamp. This recess also extends transversely over the top of the package. Thus, when the rear closure flap, to which the revenue stamp is joined, is raised, a plurality of cigarettes in the central portion of the package become readily accessible to the user.

After a cigarette has been removed, the flap may again be closed until another cigarette is desired. It will be seen from the foregoing construction that the herein described container can be manufactured at precisely the same cost as the present conventional container, since the only change in the container proper is in the slot or opening which is formed in the front wall and front closure flap.

In the drawing, Fig. 1 is a perspective view of the embodiment in its preferred form, the view showing the container in an opened condition; Fig. 2 is a broken front elevation of the closed container; Fig. 3 is a broken side elevation thereof; and Fig. 4 is a section taken on line 4—4 of Fig. 3.

As previously stated, the main body of the container is largely identical with the conventional container in which the popular brands of cigarettes are sold and comprises an outer cover 5 of paper and an inner cover 6 of laminated construction, usually comprising tin foil on the outside and paper on the inside.

The lower end of the container is permanently closed by means of a suitable adhesive and the upper end of the inner portion, which projects somewhat above the upper end of the outer cover, 55

is first folded inwardly on the two short edges to form closure flaps 7 and 8. The front portion 9 on the long edge is then folded, and finally the rear portion 10 is folded in place.

5 In the present improved container, which forms the subject matter of my invention, the front portion or closure flap 9 is provided with a centrally disposed rectangular cut-away portion 11 which extends a short distance into the vertical front wall 12 of the container, the lower edge of this recess being designated as 13. The width of the recess is somewhat less than the width of the revenue stamp 14 which is placed at the upper end of all cigarette containers. The 10 revenue stamp is positioned in substantially the same location as in the conventional container, except that its end portion 15 which engages the rear wall 16 is positioned somewhat higher than in the conventional container, and the front portion 16 extends downwardly on the front wall 12 a correspondingly greater distance. Thus, when the revenue stamp is secured in place, in the 15 position shown in Fig. 3, the recess in the top and front walls of the container is completely 20 covered.

15 The front portion of the stamp is desirably provided with a transverse scoring a slight distance from its lower end in order to form a tab or finger engaging portion 17 which projects outwardly from the front 12, all as shown in Fig. 3.

20 Inasmuch as the rear closure flap 10 does not completely cover the exposed cigarettes when in a closed position, but rather are these remaining cigarettes engaged and covered by the revenue stamp, it is desirable that the adhesive on the lower surface of the tab be applied in such a fashion as not to come in contact with these cigarettes. To accomplish this, the stamp is provided with a narrow, longitudinal glue strip 25 18 on each side thereof, which glue strip at the front end portion stops just short of the edge in order that the portion 17 may be readily grasped by the fingers.

25 The lower end of the front portion of the stamp may, if desired, be provided with a transverse glue strip but it is not essential to provide an air-tight seal since most cigarette containers are further provided with an external covering of glasive paper or "cellophane" which retains 30 the moisture in the tobacco.

30 Also the position of the revenue stamp may be varied at some length without departing from the spirit of the invention. It is desirable, however, to have at least a portion thereof adhesive-

ly joined to the rear outer wall 16 in order that the container, prior to opening, be held in its rectangular shape.

5 It may be pointed out in this connection that the Commissioner of Internal Revenue is specifically authorized to alter the form, size, or shape of the revenue stamp and accordingly it is contemplated that a wider or longer stamp may be employed, if desired, to more effectively carry out the invention. If the longer stamp were employed, the two end portions could extend downwardly on the vertical side walls of the container an equal distance, thus giving the completed container a more symmetrical appearance.

10 It will be appreciated, however, that if the 15 revenue stamp be placed in another portion of the container, any rectangular strip, whether integrally formed with the rear wall of the container or not, may be employed to carry out the 20 invention.

What I claim is:—

1. In a container for cigarettes and the like, a substantially rectangular casing which is permanently closed at its lower end and is provided with integrally formed closure flaps along its 25 four upper edges, the front closure flap having a centrally disposed rectangular cut-away portion extending from its upper edge to a point below the upper edge of the front wall of the container, the rear closure flap being positioned over 30 the front closure flap when in a closed position, a rectangular member of greater width than the width of the cut-away portion adhesively joined to the front and rear walls and to the closure flaps, retaining the latter in position, the lower 35 front portion of said rectangular member being unsecured to said front wall and forming a tear tab.

2. A container made from flexible material and having at one end thereof projecting portions 40 integrally formed with the side walls and being folded inwardly to form top closure flaps, the closure flap on the front wall having a centrally disposed opening therein which extends into the front wall, the closure flap on the rear wall being 45 folded over the front flap and means for retaining said flaps in a closed position, said means comprising a revenue stamp of greater width than the width of the opening and being adhesively joined to the top, front and rear walls, 50 the lower end of the front portion extending beyond the opening in the front wall and having a portion free from adhesive to serve as a tear tab.

JOHN D. BROPHY.
